UNITED STATES PATENT OFFICE.

GUSTAV SOBOTKA, OF NEW YORK, N. Y., ASSIGNOR TO FLEISCHMANN & CO., OF SAME PLACE.

GUARD FOR FERMENTING-VATS.

SPECIFICATION forming part of Letters Patent No. 444,944, dated January 20, 1891.

Application filed October 17, 1890. Serial No. 368,464. (No model.)

To all whom it may concern:

Be it known that I, GUSTAV SOBOTKA, of the city of New York, in the county of New York and State of New York, a citizen of Austria-Hungary, have invented certain new and useful Improvements in Guards for Fermenting-Vats, of which the following is a specification.

This invention relates to improvements in vats, tubs, or receptacles containing liquids of a foaming nature; and the object of my invention is to provide a guard for such vessels, which guard can be raised or lowered, according as the foaming of the contents of the vessel increases or decreases.

The invention consists in the combination, with a vat, of a series of rings guided to move up or down on the top of the same and a flexible sleeve connecting said rings.

The invention also consists in the construction and combination of parts and details, which will be fully described hereinafter, and finally pointed out in the claim.

In the accompanying drawings, Figure 1 is a vertical transverse cross-sectional view showing the guard lowered, parts being broken out. Fig. 2 is a similar view showing the guard raised; and Fig. 3, is a sectional plan view on the line $x-x$, Fig. 2.

Similar letters of reference indicate corresponding parts.

On the rim of the vat, tub, or vessel A a wooden ring B is secured, and from said ring four or more or less iron rods J project upward, their top ends being fastened in the ceiling of the room in which the vessel is placed. Said rods pass through two rings D D', adapted to slide up and down on the said rods. The fixed ring B and the sliding rings

D D' are connected by a sleeve C of fabric, rubber, cloth, or any other analogous flexible material, the height of said sleeve of flexible material being dependent on the height of the

room. The cloth or fabric is fastened securely to the inner sides of the rings and the edges are sewed tightly together. To the uppermost ring chains or cords E are fastened, which pass over pulleys F, and are provided at their opposite ends with counter-weights G. As the foam in the tub or vessel rises, the uppermost ring D' is raised to a certain height, it being held in place by the counter-weights, and thus forms a cylindrical guard on the top of the vat or tub and prevents the overflowing and loss of its foaming contents. If the guard is not of sufficient height and the foam passes over the top, the upper ring D' is raised still higher and the intermediate ring D raised correspondingly. The guard can easily be adjusted to any desired height, as circumstances may require, and thus does away with the necessity of using the expensive high tubs used heretofore to prevent the overflowing of the foam in the vessel.

Having thus described my invention, I claim as new and desire to secure by Letters Patent—

The combination, with a vat, of a series of guide-rods projecting upward from the top of the same, rings of the same diameter as the top of the vat, through which rings the guide-rods pass, so as to adapt said rings to slide on said guide-rods, a collapsible sleeve open at the top and bottom and secured to said rings and to the top of the vessel, and counter-balancing-weights connected with the top ring for the purpose of forming a collapsible vessel open at the top, substantially as set forth.

In testimony that I claim the foregoing as my invention I have signed my name in presence of two subscribing witnesses.

GUSTAV SOBOTKA.
